UNITED STATES PATENT OFFICE.

JOHN P. SHAW, OF ABERDEEN, MISSISSIPPI.

DESIGN FOR A MEMBER OF A STOCK-MARKING TOOL.

SPECIFICATION forming part of Design No. 29,308, dated September 6, 1898.

Application filed March 27, 1897. Serial No. 629,616. Term of patent 7 years.

To all whom it may concern:

Be it known that I, JOHN P. SHAW, a citizen of the United States, and a resident of Aberdeen, in the county of Monroe and State of Mississippi, have invented and produced a new and original Design for a Member of a Stock-Marking Tool; and I do hereby declare that the following is a full, clear, and exact description of the invention, which will enable others skilled in the art to which it appertains to make and use the same, reference being had to the accompanying drawings, which form a part of this specification.

My invention relates to a new and novel design for a member of a stock-marking tool; and the leading feature consists in the peculiar shape or configuration given to the head thereof—that is to say, the outer end or portion of the head is tapered to a point, while the inner portion is also tapered or inclined inwardly, the broadest part of the head being about midway of the ends thereof.

In the accompanying drawings, Figure 1

represents a perspective view of a member of a stock-marking tool constructed in accordance with my design, looking from the front. Fig. 2 is a rear perspective view. Fig. 3 is a transverse sectional view.

In the said drawings the reference-numeral 1 designates a member of a stock-marking tool and comprises the handle and the head 2. This head has its outer portion tapered or inclined to a point and the inner portion also tapered or inclined inwardly or toward its junction with the handle.

Having thus fully described my invention, what I claim is—

The design for a member of a stock-marking tool, substantially as shown and described.

In testimony that I claim the foregoing as my own I have hereunto affixed my signature in presence of two witnesses.

JOHN P. SHAW.
